UNITED STATES PATENT OFFICE.

JOHN E. BELL, OF BROOKLYN, NEW YORK, ASSIGNOR TO POWER SPECIALTY COMPANY, OF NEW YORK, N. Y., A CORPORATION OF NEW YORK.

SOOT-BLOWING PROVISION.

Application filed September 17, 1923. Serial No. 663,108.

To all whom it may concern:

Be it known that I, JOHN E. BELL, a citizen of the United States, and resident of Brooklyn, in the county of Kings and State 5 of New York, have invented certain new and useful Improvements in Soot-Blowing Provisions, of which the following is a specification.

My present invention relates particularly 10 to fluid heating apparatus of the type in which the fluid to be heated is circulated through tubes ordinarily formed of wrought metal which are encased in blocks of cast iron or steel each formed with a channel 15 snugly receiving a corresponding portion of the length of the tube encased by it, and in which the casing sections unite to form a wall-like structure having one side exposed to the interior of the heating chamber and 20 absorbing heat therefrom wholly or largely by radiation as distinguished from contact with, and conduction from the heating gases in the chamber. Such apparatus is well adapted for use in superheating steam, 25 cracking oil and other purposes.

The main object of my invention is to provide apparatus of the type referred to with soot blowing provisions i. e. provisions for blowing soot and ashes or other furnace 30 dust from the heat absorbing faces of the apparatus. In accordance with the present invention I provide apparatus of the character described with effective soot blowing provisions by enlarging a portion of the 35 tube receiving passage in one or more of the casing sections between the ends of the section so that when the corresponding tube is inserted in each such section, the enlargement forms a circular channel about the 40 tube. A suitable cleaning fluid as compressed air or steam is supplied to each such channel as by means of a suitable pipe connection to the side of the casing section remote from the furnace chamber, and this 45 fluid is discharged through an opening formed in the casing section and leading from the channel to the face of the section exposed to the furnace chamber, suitable discharge nozzle provisions being made for 50 causing the heating fluid to be discharged in jets sweeping over the heat absorbing face of the wall formed by the casing section.

The various features of novelty which characterize my invention are pointed out

with particularity in the claims annexed 55 to and forming a part of this specification. For a better understanding of the invention however, its advantages and specific objects attained with its use reference should be had to the accompanying drawings and 60 descriptive matter in which I have illustrated and described preferred embodiments of my invention.

Of the drawings:

Fig. 1 is a diagrammatic sectional elevation of a boiler furnace;

Fig. 2 is an elevation of a portion of the furnace chamber wall of Fig. 1, in which a superheater is incorporated;

Fig. 3 is a partial section on the line 3—3 70 of Fig. 2;

Fig. 4 is a partial section on the line 4—4 of Fig. 3; and

Fig. 5 is a view taken similarly to Fig. 4 75 illustrating a modification.

In the drawings, A represents a boiler furnace having a water tube boiler A' of conventional design mounted above a furnace chamber A². Incorporated in one of the walls of the furnace chamber is a radiant heat superheater B comprising a row of parallel tubes b having outturned ends connected to the superheater inlet and outlet headers B' and B², respectively. The tubes b which are formed of wrought iron 80 or steel, are encased in block-like sections b' of cast iron or steel. The various sections b' unite to form a wall-like structure having a smooth heat absorbing face exposed to the furnace chamber A.

In accordance with the present invention the superheater B is provided with soot blowing provisions comprising discharge nozzles C provided at suitably spaced points over the heat absorbing face of the superheater and carried by the corresponding tube casing sections b'. As shown in Fig. 1, 2, and 3, the nozzle members C are removable parts screwed into threaded openings D' formed in the corresponding casing sections b'. Each opening D' communicates at its inner end with a circular channel D formed in the corresponding casing section b' about the tube b passing through their casing section. Cleaning fluid as compressed air or steam, and preferably the latter, is supplied to each channel D through a corresponding opening D² leading to the rear 100 105

face of the section and connected through suitable branch pipes E from pipes E' connected by valves E² to a cleaning fluid supply pipe E³ at the outer side of the super-
5 heater.

In the practical construction of the type of heat absorbing apparatus disclosed, it is necessary to bore or ream out the channels in the casing sections b' in which the tubes b 10 are received to insure a sufficiently close fit, the casing sections b' being ordinarily shrunk onto the tubes b thus insuring tight joints between the device and the casings. When a casing section b' to be provided 15 with soot blowing provisions, is being bored or reamed out, it is a simple and relatively inexpensive matter to form a channel D therein with a suitable milling cutter or reaming tool, and this mode of forming the 20 channels D is the one which I now consider preferable from a practical standpoint, although it is possible in some cases to form the channels D in casting the casing section b' provided with such channels. Each nozzle C 25 is provided with discharge orifices C' arranged to discharge the cleaning fluid in jets sweeping over the heat absorbing faces of the sections D'. As shown each nozzle C is formed with a plurality of radially 30 extending discharge orifices C'. The soot blowing provisions above described are simple and effective and relatively inexpensive. With the tubes b forming the inner 35 wall of the channels D, the latter may be made of ample cross section without objectionably weakening the sections b' or seriously impairing their heat conducting properties.

In lieu of employing removable nozzles 40 C, tube casing sections b¹⁰ provided with soot blowing provisions comprising integral nozzle lugs b¹¹ on their heat absorbing faces, may be employed as shown in Fig. 5. In this case the openings D' and D² may be 45 drilled at the same operation from the rear side of the casing section, and the discharge orifices holes b¹² are then drilled into the nozzle lug b¹¹. The construction shown in Fig. 5 is somewhat simpler than that 50 shown in Figs. 2, 3, and 4, but the use of the removable nozzle parts C shown in the first described construction permits ready renewal of the nozzle parts in case of deterioration of the latter under the severe conditions to which they are exposed. The 55 invention disclosed and claimed herein is a specific improvement on the invention disclosed and generically claimed in my prior

application, Serial No. 634,712, filed April 26, 1923.

While in accordance with the provisions of the statutes I have illustrated and described the best forms of my invention now known to me, it will be apparent to those skilled in the art that changes in the form 65 of the apparatus disclosed may be made without departing from the spirit of my invention as set forth in the appended claims.

Having now described my invention, what I claim as new and desire to obtain by Letters Patent is;

1. In a fluid heating apparatus comprising parallel tubes encased by metal sections uniting to form a wall-like structure having a smooth heat absorbing face, the improvement which consists in enlargements of the tube receiving passages of some of said sections, whereby each such enlargement forms a channel in the corresponding section about the tube passing through that section, connections for supplying cleaning fluid to said channels, and nozzle provisions connected to said channels for discharging the cleaning fluid over the heat absorbing surface of the apparatus.

2. In a radiant heat absorbing superheater comprising parallel tubes enclosed in metal sections uniting to form a wall-like structure having a smooth heat absorbing face, the improvement which consists in enlargements of the tube receiving passages of some of said sections whereby each such enlargement forms a circular channel in the corresponding section about the tube passing through that section, connections for supplying cleaning fluid to said channels and nozzle provisions connected to said channels for discharging cleaning fluid over said face.

3. Fluid heating apparatus comprising a tube and a metallic casing block having a passage in which the tube is snugly received at the ends of the block and which is enlarged between the ends of the block to provide a cleaning fluid channel about the tube, an inlet opening to said channel to one side of said block, and a discharge nozzle outlet from said channel at the opposite side of the block arranged to cause the cleaning fluid discharged to sweep the last mentioned side of said block.

Signed at New York city in the county of New York and State of New York this 14th day of September A. D. 1923.

JOHN E. BELL.
